REINHOLD H. WAPPLER, OF NEW YORK, N. Y., ASSIGNOR TO AMERICAN CYSTOSCOPE MAKERS, INC., OF NEW YORK, N. Y.

HANDLE FOR ILLUMINATIVE DIAGNOSTIC AND SURGICAL INSTRUMENTS.

1,162,198.

Specification of Letters Patent. Patented Nov. 30, 1915.

Application filed April 21, 1915. Serial No. 22,790.

To all whom it may concern:

Be it known that I, REINHOLD H. WAPPLER, a citizen of the United States, and a resident of New York city, county and State of New York, have invented certain new and useful Improvements in Handles for Illuminative Diagnostic and Surgical Instruments, of which the following is a specification.

10 This invention relates to a novel handle more particularly adapted for supporting instruments for diagnostic and surgical illumination of inner organs of a patient. The handle includes novel means for regulating the current applied to the electric bulb and for preventing a premature burning out of the lamp, owing to the application of a current of excessive voltage.

15 The invention also contains other novel features of construction as more fully brought out in the appended specification and claims.

20 In the accompanying drawing, Figure 1 is a side view of a handle embodying my invention, showing a light tube attached thereto; Fig. 2 an enlarged longitudinal section through the handle with the light tube partly broken away; Fig. 3 an enlarged side view of the upper portion of the handle with the barrel detached; and Fig. 4 a cross section on line 4—4, Fig. 2.

25 My improved handle comprises essentially a barrel 10 into one end of which is tapped a conductive nipple or sleeve 11. The latter is provided with a stepped axial bore 12 adapted for the reception of the correspondingly shaped lower end 13 of a plug 14 made of insulating material. The upper reduced end 15 of plug 14 is snugly encompassed by a conductive socket 16 adapted for the reception of the foot 17 of a diagnostic lamp tube or a similar illuminative instrument 18, that is held in position by a screw 19. Into plug 14 is tightly fitted a 30 metallic tube 20 the upper end of which is frictionally engaged by the contact pin 21 of lamp 18.

35 Intermediate sleeve 11 and socket 16 there is wound upon plug 14 a resistance coil or rheostat 22 one end of which is connected to socket 16 by a screw 23. Across the several windings of rheostat 22 is adapted to ride a contact spring 24 received within a corresponding recess of a slide 25 encompassing sleeve 11. Spring 24 is provided

40 with an outwardly bent end 26 which engages a perforation 27 of said slide so that the contact spring participates in the movement of the slide. Back of a flange 28, socket 16 is provided with a split ring 29 that frictionally engages said socket and constitutes an adjustable stop for the slide.

45 The electric current is furnished from a suitable source (not shown) through a flexible twin cord 30 that passes through barrel 10, the two conductors 31, 32 of said cord being respectively connected to tube 20 and sleeve 11.

50 In the position illustrated in Figs. 1 and 2, contact 24 is out of engagement with rheostat 22 so that the current is cut off from the lamp 33 of tube 18. If slide 25 is moved outward, the lamp circuit will be closed, the current flowing as follows:— 55 from the source of electricity through wire 31, tube 20, pin 21, lamp 33, foot 17, socket 16, rheostat 22, contact 24, sleeve 11, and wire 32 back to said source. It will be seen that the farther slide 25 is moved outward, 60 the less resistance is interpolated into the lamp circuit, thereby increasing the brilliancy of the lamp.

65 As my improved handle is designed to be used in conjunction with instruments of different character requiring a different illuminative power, which in turn determines the electric current necessary for the lamp, it is obvious that the filaments of relatively small lamps may be readily over-loaded if the full current is applied thereto. In order 70 to overcome this difficulty the stop 29 is provided which limits the outward movement of slide 25. This stop is so set that whenever the slide is shifted outward until its movement is checked by said stop, a predetermined part of the rheostat remains 75 interpolated in the lamp circuit thus preventing a premature burning out of the lamp.

80 I claim:—

85 1. A handle of the character described, comprising a barrel, a conductive sleeve mounted therein, an insulated plug mounted in the sleeve, a conductive socket 90 encompassing one end of the plug, an illuminative instrument having a conductive foot that is received within the socket, a resistance coil encompassing the plug, and connected at one of its ends to the socket, a 95 slide movable along the sleeve, a contact 100

105

110

spring on the slide that is adapted to engage the resistance coil, an adjustable stop for the slide, and a source of electricity metallically connected at its poles to the lamp 5 and to the sleeve respectively.

2. A handle of the character described, comprising a barrel, a conductive sleeve mounted therein, an insulated plug mounted in the sleeve, a conductive socket encompassing one end of the plug, an illuminative instrument having a conductive foot that is received within the socket, a contact

pin on said instrument, a metallic tube fitted within the plug and adapted to receive the pin, a resistance coil encompassing the plug 15 and connected at one of its ends to the socket, a slide movable along the sleeve, a contact spring on the slide that is adapted to engage the resistance coil, an adjustable stop for the slide, and a source of electricity 20 connected at its poles to the tube and to the sleeve respectively.

REINHOLD H. WAPPLER.
